MICHAEL M. KAUFMANN AND JOHN P. LYNN, OF CHICAGO, ILLINOIS, ASSIGNEES TO
PHILIP P. THOMAS, TRUSTEE, OF MINNEAPOLIS, MINNESOTA.

MECHANICAL PENCIL.

1,353,345.

Specification of Letters Patent. Patented Sept. 21, 1920.

Application filed February 11, 1920. Serial No. 358,005.

To all whom it may concern:

Be it known that we, MICHAEL M. KAUFMANN and JOHN P. LYNN, residing at Chicago, in the county of Cook and State of Illinois, have invented certain new and useful Improvements in Mechanical Pencils; and we do hereby declare the following to be a full, clear, and exact description of the invention, such as will enable others skilled 10 in the art to which it appertains to make and use the same.

This invention relates to a mechanical pencil, and has for its object to provide a simple, neat and efficient device of this 15 character which can be readily constructed without the use of special machinery and equipment, and which has very few and simple parts.

The invention consists in the features of 20 construction and combinations of parts hereinafter fully described and particularly claimed.

In the accompanying drawings illustrating 25 a suitable embodiment of the invention:

Figure —1— is a central longitudinal section of a pencil constructed in accordance with the invention a part of the tip and cylindrical portion of the barrel being broken away.

Figs. —2— and —3— are respectively 30 transverse sections on an enlarged scale on the lines 2—2 and 3—3 of Fig. 1.

The said pencil comprises the barrel 1 terminating at one end in the tapered tip 35 portion 2, the extreme end of which is longitudinally slotted to render it expansible. This extreme end has a bore which is normally of slightly less diameter than the leads adapted to be projected therethrough and is 40 adapted to be slightly expanded when leads are forced therethrough by the projecting means hereinafter described.

Mounted concentrically within the barrel 1 is a lead tube 4 which is suitably held in 45 place therein and extends from a point within the tapered tip portion of the barrel inwardly of the expansible end thereof to the other open end of said barrel 1. This tube has an inner diameter slightly larger than that of 50 the leads adapted to be received therein, and is disposed in axial alignment with the bore

in the tip through which the leads are to be projected.

The barrel is internally threaded, as at 5, in its cylindrical end portion for engaging 55 the lead projecting mechanism. The latter comprises the cap member consisting of an outer sleeve or tube 6 which is adapted to telescopically receive the open end portion of the barrel and is provided in its extreme opposite end portion with a plurality of longitudinal slots 7 extending from a point adjacent the extreme outer end thereof a short distance inwardly. This slotted portion of 60 said tube 6 is very slightly bellied, as indicated at 8, said bellied portion being obviously flexible and adapted to yieldingly engage the hollow shank of the closure cap 9. Within the bellied portion of said tube 7 an eraser 10 is adapted to be engaged so that 65 upon removing the closure cap 9 said eraser may be used.

Within the said tube 6 and concentric therewith there is mounted an externally threaded tube 11 terminating at one end in 75 an annular edge flange 12 having an outer annular edge which snugly fits the bore of the tube 6 and is soldered or otherwise rigidly secured therein. The said annular flange is preferably integral with a central 80 portion or plug 13. Secured in the central portion of said plug 13 and extending downwardly to a point contiguous to the inner end of the tube 6 is a small tube 14 having a bore sufficiently large to telescopically receive the lead tube 4. One end portion of the tube 14 is slightly annularly reduced as at 14^a to fit the central opening in the plug member 12 and is rendered rigid with the latter. Extending centrally of said 85 tube 14 is the rod or plunger 15 which projects from the mouth thereof, and which is also slightly annularly reduced at its other end portion as at 15^a to fit the contracted bore of the portion 14^a of said tube 14 and is 90 made rigid with the latter.

The annular space 17 between the tube 14 and the externally threaded tube 11, which also extends to a point contiguous to the inner end of the tube 6, constitutes a 100 suitable magazine for extra leads, and is preferably closed to prevent leads dropping

out of same and into the barrel 1, when the pencil is in use, by means of a suitable removable cap 16. The closure cap 16 is provided with lugs or projections 18 for digitally engaging said cap.

The leads adapted to be used in the pencil may be of any desired length within certain limits. Assuming, for example, that the barrel 1 is about four inches long, it 10 would be preferable to use leads of one inch and a half in length each, and drop two of the same into the lead tube 4 successively. In that case the externally threaded tube 11 would be about one and one-half inches long 15 and the plunger rod 15 would so far project from the said externally threaded tube 11 that upon engaging about one-quarter inch of the threads of said externally threaded tube 11 with the threads of the barrel 1 20 the first of the two leads in the lead tube 4 will be projected to extend about one-eighth of an inch from the tip 2. Thus as soon as one lead has been completely exhausted, the next lead will be engaged within the slotted 25 portion of the tip 2, but will not project therefrom and thereupon it will be necessary to reversely rotate the cap member to remove the same from the barrel 1 and drop another lead into the lead tube 4, and thereupon replace the cap member.

The threads are preferably of such pitch as will not require a great many revolutions of the cap member relatively to the barrel to remove said cap from the latter 30 for the purpose of inserting new leads, it being only necessary that such threads shall not be of so steep a pitch as to cause reverse rotation of the parts by the pressure exerted by the lead during the operation of writing. It will be noted that when the cap is removed from the barrel there is no mechanism visible except the projecting end 40 of the plunger 15 and the cap 16 for the magazine, since the threads of the externally threaded tube 11 are not exposed to view.

The longitudinal slots 7 in the outer end portion of the tube 6 also permit the insertion of a pin, or similar sharp instrument, into said slots for the purpose of engaging 50 and removing a worn-down eraser from the outer end of the tube 6 for the purpose of inserting a new eraser.

While we have shown the preferred embodiment of the invention in the accompanying drawings, it will be understood, of course, that such embodiment may be changed and varied in details of construction without departing from the invention as defined in the appended claims.

60 We claim as our invention:

1. A mechanical pencil comprising a barrel open at one end and terminating at its other end in a tapered tip adapted for resisting the passage of leads from said barrel, a lead tube mounted concentrically within

said barrel and extending from a point within the tapered tip portion thereof to the open end of the same, a cap member for said barrel comprising a sleeve adapted to telescopically receive the open end of the 70 barrel, an externally threaded tube rigid and concentric with said sleeve and extending from the outer end portion to substantially the mouth thereof, the cylindrical portion of the barrel being internally 75 threaded to engage said externally threaded tube of said cap member, a lead projecting plunger rigid with and mounted axially of the cap member and projecting from the inner end thereof and adapted to enter the 80 inner end portion of the lead tube for effecting projection of leads from the barrel as said cap member is rotated relatively to said barrel in one direction.

2. A mechanical pencil comprising a 85 barrel open at one end and terminating at its other end in a tapered tip, adapted for resisting the passage of leads from said barrel, a lead tube mounted concentrically within said barrel and extending from a 90 point within the tapered tip portion thereof to the open end of the same, a cap member for said barrel comprising a sleeve adapted to telescopically receive the open end of the barrel, an externally threaded 95 tube rigid and concentric with said sleeve and extending from the outer end portion to substantially the mouth thereof, the cylindrical portion of the barrel being internally threaded to engage said externally threaded tube of said cap member, a lead projecting plunger rigid with and mounted axially of the cap member and projecting from the inner end thereof and adapted to enter the inner end portion of 100 the lead tube for effecting projection of leads from the barrel as said cap member is rotated relatively to said barrel in one direction, said externally threaded tube substantially corresponding in length with that of 110 the leads adapted to be projected from said barrel and adapted to effect a shortening of the pencil a length substantially equal to the length of one of said leads during projection of the latter from said barrel 115 throughout the length of said lead.

3. A mechanical pencil comprising a barrel open at one end and terminating at its other end in a tapered tip, adapted for resisting the passage of leads from said barrel, 120 a lead tube mounted concentrically within said barrel and extending from a point within the tapered tip portion thereof to the open end of the same, a cap member for said barrel comprising a sleeve adapted to 125 telescopically receive the open end of the barrel, an externally threaded tube rigid and concentric with said sleeve and extending from the outer end portion to substantially the mouth thereof, the cylindrical por- 130

tion of the barrel being internally threaded to engage said externally threaded tube of said cap member, a lead projecting plunger rigid with and mounted axially of the cap member and projecting from the inner end thereof and adapted to enter the inner end portion of the lead tube for effecting projection of leads from the barrel as said cap member is rotated relatively to said barrel in one direction, a tube concentric and rigid with said sleeve and plunger adapted to telescopically receive the lead tube and termin-

nating at its free end substantially at the mouth of the externally threaded tube, the annular space between the latter and said inner tube of said cap member constituting a magazine for leads corresponding in length substantially with the leads adapted to be projected from the pencil, and a closure cap for said magazine adapted to be removably engaged with one of said inner tubes of said cap member.
